Fig. 10

Fig. 11

FIG. 1 is a front perspective view of a calculator showing my new design and shown with the cover removed;

FIG. 2 is a front elevation of the calculator;

FIG. 3 is a top view thereof;

FIG. 4 is a side elevation thereof;

FIG. 5 is a rear elevation thereof;

FIG. 6 is a front perspective view of a removable cover for the calculator;

FIG. 7 is a front perspective view of the calculator with the removable cover in place;

FIG. 8 is a top view thereof;

FIG. 9 is a side elevational view of the removable cover, the opposite side being a mirror image thereof;

FIG. 10 is a front elevation thereof; and

FIG. 11 is a rear elevation thereof.

I claim:

The ornamental design for a calculator, as shown and described.
